ELECTRIC SAFETY LAMP

Filed Aug. 27, 1928

UNITED STATES PATENT OFFICE

JOHANNES BECKMANN, OF ALTONA, OTTENSEN, GERMANY

ELECTRIC SAFETY LAMP

Application filed August 27, 1928, Serial No. 302,202, and in Germany June 4, 1928.

Electric lamps for lighting spaces or containers filled with explosive gases require special attention in order that the explosive gas is not ignited by a contact spark at the switching in of a circuit for the glow lamp bulb. A condition for a lamp of this type working with absolute reliability is, to have a permanent control that all elements in the lamp are in order and packed against the outer air, so that no explosive gases can filter into the lamp casing where they might come in touch with contact sparks.

This security and control of the reliability is obtained, according to the invention, which relates to a lamp for lighting containers filled with explosive gases or liquids, by composing the lamp of two compressed air chambers communicating the one with the other by a tube, one chamber serving to accommodate the bulb with holder, cap and wire guard, the other compressed air chamber containing a switch to be operated by compressed air and designed to close the circuit for the bulb so that in both compressed air chambers and in the cap exists continually similar over pressure and if any leakage occurs, the circuit will be automatically cut out by outflowing of compressed air, whereby any danger of explosion is avoided.

Two embodiments of the invention are illustrated, by way of example, in the accompanying drawing in which

Fig. 1 is a longitudinal section, showing the electric lamp with cut-out circuit to be connected to an existing cable.

Fig. 2 is a similar view, partly in elevation, the contact being closed and a battery used as source of current.

Fig. 3 shows the lamp contact on larger scale in section.

Fig. 4 shows on smaller scale the electric lamp in elevation.

The lamp, according to the invention, consists of a compressed air chamber 1 and of a compressed air chamber 2, connected the one with the other by a tube 3. In the chamber 2 the holder 4 with a bulb 5 and a cap 6 are mounted, the latter being directly connected to the chamber 2 which communicates with the chamber 1 by channel 7 and

the tube 3. The compressed air chamber 1 serves for accommodating a switch to be operated by compressed air and consisting, in the form of construction shown, of a cylinder 8 mounted in a partition 9 of insulating material so that it is insulated against all other elements of the lamp. In the cylinder 8 a piston 12 is arranged which is controlled by a spring 10 and has a contact pin 11, said piston adapted to be shifted in its cylinder 8 by the pressure in the chamber 1 in opposition to the action of spring 10 so that the contact pin 11 can penetrate into a contact sleeve 13 which is also insulated so that the circuit for the bulb is closed. The circuit is formed by a lead 14 and leads 15, 16, the lead 15 being connected to the contact sleeve 13 and the lead 16 to the cylinder 8. The lead 14 is connected to the one pole of the bulb 5 and the lead 16 to the other pole of the same. The other ends of the leads 14 and 15 are connected to a source of current.

The partition 9 of insulating material serves further to pack the chamber 1 against the outer air.

A check valve 17 in said partition serves for admitting the compressed air into the chamber 1, tube 3, channels 7, chamber 2 and cap 6.

In order to prevent filtering of explosive gases into the contact sleeve 13 arranged outside the compressed air chamber 1, this sleeve 13 is airtightly closed by a hood 18 which communicates with the chamber 1, a packing 19 being interposed.

The leads 14, 16 have hollow contact screws 20 by means of which they are connected to the bulb 5, contact pins 22 controlled by springs 21 being shiftably arranged in said hollow contact screws 20 so that they can engage with contact projections 23 on the foot 24 of the bulb 5.

In order to ensure proper contact between the movable pins 22 and the projections 23 at the insertion of the bulb, the foot 24 carries a ring 25, a projection 26 of which engages with the holder 4 against which the ring is pressed by a cap nut 27. The ring 25 serves therefore at the same time for

centering the bulb 5 and for fixing the same on the holder 4.

The form of construction shown in Fig. 2 is designed for such cases where no stationary cable exists, so that a separate source of current has to be used. With this object in view a battery 28 is mounted in an upwardly directed extension of the hood 18 which is airtightly packed by a screw cap 29.

10 The cap 6 is enclosed by a wire cage 30 and the casing of the chambers 1 and 2, as well as the hood 18, are enclosed by insulating protecting envelopes 31.

15 To use the lamp compressed air is forced through the check valve 17 into chamber 1, tube 3, chamber 2 and through the channels 7 into the cap 6. As soon as the pressure has attained a predetermined degree the piston 12 is pushed upward in the cylinder 8 against the action of spring 10 so that the contact pin 11 engages with the contact sleeve 13, whereby the circuit is closed and the bulb 5 lighted.

20 25 If any leakage occurs the compressed air has the tendency to escape through the same so that surrounding explosive gases are kept away from the leaky point and can not penetrate into the chambers.

30 35 As soon as the pressure in the chambers decreases the spring 10 pushes back the piston 12 so that the contact pin 11 disengages from sleeve 13, the circuit being therefore automatically cut out before dangerous gases can touch any contact sparks.

35 Owing to the fact that the circuit is closed by the action of compressed air the best control is given so that the lamp is ready for use and secure in service.

40 I claim:

45 1. An electric lamp comprising in combination with a chamber with check valve and pneumatic switch and with a second chamber and the lamp holder, hollow contact screws in said lamp holder, spring-controlled contact pins in said contact screws, a lamp foot, hollow contact projections of said lamp foot designed to receive said contact pins, a ring having a projection adapted to centre said holder, and a screw cap for fixing said ring on said holder.

50 55 2. An electric lamp as specified in claim 1, comprising in combination with the upper airtight chamber an upwardly directed extension of said chamber; an electric battery in said extension, and a screw cap airtightly closing said extension.

In testimony whereof, I affix my signature.

60 JOHANNES BECKMANN.
